UNITED STATES PATENT OFFICE

ALFRED T. HOPKINS, OF DETROIT, MICHIGAN

PACKING HOLDER FOR COATS AND OTHER GARMENTS

Application filed November 24, 1924. Serial No. 751,953.

The invention relates to a garment packing device designed to facilitate the folding of garments into a small compact bundle suitable for packing in trunks or suitcases without unduly wrinkling or destroying the press of the same.

The object of the invention is to provide a device having means for supporting the shoulders of the garment and also having means whereby the lower portions of the garment may be folded around parallel edge portions. Another object of the invention is to provide a device permitting the folding of sleeved garments into a compact bundle without wrinkling the shoulders and sleeved portions of the garment.

These and other objects are obtained by the novel constructions hereinafter more fully described and illustrated in the accompanying drawings wherein:

Figure 1 is a perspective view of the packing holder;

Figure 2 is a transverse section on the line 2—2 of Figure 1;

Figure 3 is a perspective view of the device shown in Figure 1 after a suit has been placed thereon;

Figure 4 is a perspective view of the device showing a modified construction;

Figure 5 is a transverse section thereof;

Figure 6 is a plan view of the device illustrating the method of packing the garment.

In the embodiment of my invention illustrated in Figures 1 to 3 the packing holder comprises a frame A having spaced rounded bars B and C respectively connected at their outer edges by the cross members D and D'.

E is a supporting member adapted to be inserted in the upper portion of the garment and is preferably formed with sloping rounded edges F for engaging the shoulders of a coat. This member is secured to the frame intermediate the bars B and C and preferably has a hinged connection with one of the bars.

As shown the connection comprises the sheet metal strap G secured to the member by the units G' and having the rounded portion G² passing around the upper rod B between the projecting pins H.

A modified structure is shown in Figures 4

to 6 wherein the frame I is made of cardboard or other suitable material and has a continuous back J extending across the frame while the front is provided with a recess K slightly larger than the supporting member L so as to provide a clearance M for the shoulders of the garment. The upper edge portion N of the frame is rounded and of a substantial thickness and the lower edge N' is similarly constructed, there being a sloping portion O connecting the latter with the surface O' forming the bottom of the recess. The upper boundaries of the recess P and P' are preferably sloped to correspond substantially to the curved surfaces Q of the supporting member and the latter is preferably formed of relatively thin material compared with the frame so that when the garment is placed thereupon the top surface L' will be substantially flush with the top surface R of the frame.

In packing a garment such as a coat S on either of the above described holders, it is preferably first placed on a flat surface such as a table or bed with the lapels S' on the upper side and the supporting member is inserted in the shoulders portion of the garment as illustrated in Figure 6. The sleeves T are then arranged smoothly on the lower portion of the coat after which the garment is folded over the lower edge N', while maintaining sufficient tension to prevent wrinkling of the cloth. In this manner the coat may be wound tightly around the parallel edge portions and when once wrapped will remain in that position occupying a minimum of space.

If desired, other garments may be wrapped around the first garment and, for example, in the packing of men's suits, the vest and the trousers are each wrapped around the bundle on top of the coat as illustrated in Figure 3. A strap U may then be placed around the completed bundle, thus securely holding the clothes in place. This arrangement results in a package of a convenient size which may readily be placed in the ordinary size suitcase or travelling bag.

What I claim as my invention is:—

1. A device for compactly folding gar-

ments for packing purposes comprising a fashioned member for engaging the shoulders of a garment, a substantially rectangular frame surrounding said fashioned member and secured thereto, said fashioned member being movable into the plane of said frame, said frame having parallel rounded marginal portions on opposite sides of said fashioned member and spaced apart by a distance less than the transverse dimension of said frame, whereby a garment having the shoulder portions supported on said fashioned member may be wrapped around said spaced marginal portions to form a compact bundle, the largest dimension of which is in the direction of the width of the garment.

2. A device for compactly folding garments for packing purposes comprising a frame having parallel rounded edge portions spaced apart by a distance less than the transverse dimension of the frame, said frame having a recess intermediate said edge portions, and a fashioned shoulder-engaging member hingedly secured to one of said edge portions and arranged in said recess between said members.

3. A device for compactly folding garments for packing purposes comprising a frame of substantial thickness having parallel rounded edge portions spaced apart by a distance less than the transverse dimension of the frame, a member fashioned for engagement with the shoulders of a garment hingedly supported on said frame to swing about an axis parallel to said edge portions, said frame having a recess therein for receiving said fashioned member and provided with clearance for the shoulder portion of the garment.

40 In testimony whereof I affix my signature.
ALFRED T. HOPKINS.
